United States Patent Office.

HENRY A. DIRKES, OF NEW YORK, N. Y.

Letters Patent No. 76,896, dated April 21, 1868; antedated April 7, 1868.

IMPROVEMENT IN BALLAST-KEELS FOR BOATS.

The Schedule referred to in these Letters Patent and making part of the same.

TO ALL WHOM IT MAY CONCERN:

Be it known that I, HENRY A. DIRKES, of the city, county, and State of New York, have invented a new and useful Improvement in Life-Boats, of which the following is a full, clear, and exact description, reference being had to the accompanying drawing, forming part of this specification, and in which—

Figures 1 and 2 represent longitudinal and transverse sections of a boat embracing my improvement.

Similar letters of reference indicate corresponding parts in both figures.

My invention consists in a combination, with the hull of a boat, of a ballast-keel, peculiarly hung and operated, and whereby, while it may be raised or lowered vertically, with facility and dispatch, either to form an ordinary keel or to project deeper and to a variable extent into the water, it is left free to play longitudinally, and rise or ride over any obstruction it may encounter in the sailing or beaching of the boat, regardless of which end of the latter may be foremost.

Referring to the accompanying drawing, A represents the hull of a boat, which may be made of any suitable material, in compartments, or otherwise, and, as life-boats are usually constructed, size and shape. It may be fitted, though not here shown, with the usual attachments or appliances for storing and propulsion, and may either be used as a ship's boat or as a life-boat, to be launched from the shore. B is the ballast-keel, preferably made of metal, and extending for the greater proportion of the length of the boat. This keel is hung to rise and fall vertically, and so that it may be set to occupy various depths in or holds on the water, preferably extending at its lowest depth below, and so as to be a detachment, as it were, from, though connected with, the bottom of the boat, to either the position of an ordinary keel, or so as to shut entirely up within the boat, and leaving the bottom flush, which may be an advantage in beaching or launching the boat from the shore. For this end or these purposes, and to give a freedom of action or adjustment, together with breaking-shock, in case of the keel, when lowered, striking an obstruction, in the movement of the boat, either end foremost, or allowing of the keel by a longitudinal action of it to rise or ride over such obstacle, I suspend said keel to the boat by any suitable number of toggle-joints, C, pivoted at their tops to the boat or casing, fitted the same, which casing may be enclosed at top, and connected at their lower ends to the keel, that, when raised, enters or shuts up into said casing, through the longitudinal slot a, made in the bottom of the boat.

To raise or lower the keel by hand, and lock it in any particular set, various contrivances may be employed. Thus the same may be effected by a screw, D, connected with the keel by any suitable joint, or it may be done by raising or lowering and locking end-chains E, or in any other way that it may be found advantageous to adopt.

A ballast-keel, hung and operated or operating as described, while it may be lowered vertically to different depths with facility and dispatch, to prevent capsizing, and aid in steadyng the boat in its course, may in like manner, and with equal facility, be raised to within the boat, with, when lowered, freedom of play longitudinally, as previously observed, in either or opposite directions, to break shock, and assist the boat in rising or riding over an obstacle. The toggle-joints C also form broad or stiffening side-braces to the keel.

What I here claim, and desire to secure by Letters Patent, is—

The ballast-keel B, hung or attached to the boat by toggle-joints C, and operating or operated substantially as described.

HENRY A. DIRKES.
